United States Patent Office.

JOHN C. MILLER, OF DANVILLE, KENTUCKY.

Letters Patent No. 82,337, dated September 22, 1868.

IMPROVED SIDE-SADDLE TREES.

The Schedule referred to in these Letters Patent and making part of the same.

TO ALL WHOM IT MAY CONCERN:

Be it known that I, JOHN C. MILLER, of Danville, in the county of Boyle, and State of Kentucky, have invented a new and useful Improvement in Side-Saddle Trees; and I do hereby declare the following to be a full, clear, and exact description thereof, reference being had to the accompanying drawing, which is made a part of this specification.

In the usual method of making side-saddle trees, the spring or pommel is left to be attached by the journeyman saddler, after the "tree" goes to him for completion as a saddle. It is in that case formed of several thicknesses of "skirting-leather," hardened and stiffened by means of tacks, thread, and paste, and the time required for its construction is generally from four to five hours, making a very tedious and expensive operation, and producing a comparatively imperfect article.

My invention consists in making the spring or pommel of the requisite width a part of the tree, as originally manufactured, and of the same or similar material.

In the drawing—

Figure 1 represents a vertical transverse section through the head of a side-saddle tree, made according to my invention, and

Figure 2 is a plan view thereof.

A may represent the body of the tree; B B, the fork, and I, the spring or near horn, all of which parts are constructed in the usual way, and of the ordinary material. D E F G are iron straps, bent to conform to the shape of the parts of the tree to which they are respectively applied, and attached by means of the rivets H H'.

C represents a piece of oak or other suitable wood, cut to the proper size, and steamed and bent to the form required, which is secured between the straps D and F, and the top of the forks B, by the rivets H, as represented in fig. 1. This piece forms the off horn c and the front or pommel c', fig. 1, and its form and relative size may be varied as may be required for the different forms of each.

The piece C, after being attached, is provided with a covering of canvas, and glue-painted, similarly to the other parts of the tree, or said covering and painting may be done previous to its attachment, when preferred.

I am aware that the horns of side-saddle trees have been made of wood with the grain lengthwise, and make no claim to that feature; but so far as I am informed, no tree, prior to my invention, has been provided in its manufacture with a front or pommel made of wood, as herein described.

I therefore claim as my invention, and desire to secure by Letters Patent—

1. As a new article of manufacture, a side-saddle tree, in which the front or pommel c' is formed at the same time and of a similar material to the body of the tree, substantially as and for the purpose specified.

2. The combined off horn and pommel C, formed from wood with the grain lengthwise, by cutting, steaming, and bending, and attached, substantially in the manner described.

To the above specification of my improvement in side-saddle trees, I have signed my hand, this 6th day of May, A. D. 1868.

JOHN C. MILLER.
